JAMES C. CONNALLY AND JOHN D. RUSSELL, OF JACKSONVILLE, FLORIDA.

FOLDING COT.

1,246,716.

Specification of Letters Patent. Patented Nov. 13, 1917.

Application filed January 8, 1917. Serial No. 141,293.

To all whom it may concern:

Be it known that we, JAMES C. CONNALLY and JOHN D. RUSSELL, citizens of the United States of America, and residents of Jacksonville, in the county of Duval and State of Florida, have invented certain new and useful Improvements in Folding Cots, of which the following is a specification.

This invention relates to folding cots and particularly to a foldable cot in which the canvas or bed bottom is held in place without the use of side rails, means being provided for stretching the canvas laterally and holding it in shape though the said device has sliding action which will operate under the weight of the occupant of the cot so that it will permit the canvas to assume positions which will insure comfort to the occupant.

A still further object of this invention is to provide a cot having foldable sections braced to produce unusual strength and durability; furthermore, the invention consists in the provision of a foldable head rest having novel means by which the said head rest is held extended or in operative position to support the head of the occupant of the cot.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification, wherein like characters denote corresponding parts in the several views, and in which

Figure 1 illustrates a view in elevation of a cot structure embodying the invention;

Fig. 2 illustrates an underneath plan view thereof;

Fig. 3 illustrates a sectional view on the line 3-3 of Fig. 1;

Fig. 4 illustrates a perspective view of a fragment of the cot;

Fig. 5 illustrates a perspective view of fragments of the cot at the end opposite that shown in Fig. 4;

Fig. 6 illustrates a perspective view of a fragment of the frame; and

Fig. 7 illustrates a perspective view of a

fragment of the strut member and a fragment of a tension member applied thereto; 55 and

Fig. 8 illustrates a perspective view of a fragment of one of the legs, and means for bracing the same.

In these drawings 10 denotes the legs and 60 as they are all of the same construction, a description of one will suffice as a description of all of them. Each leg has its upper end mounted on a stud or pivot 11, the said pivot 11 extending through an ear 12 of 65 the bracket or coupling 13, the said bracket 13 being oscillatably mounted on the pivot 14 extending through ears 15 of a head 16, which head is secured or mounted on one end of a strut-piece, which strut-piece comprises pivoted sections 17 and 18, of a construction to be hereinafter described. 70

The bracket 13 has ears 19 to which the posts 20 are connected by the members 21 so that the legs and posts may articulate 75 on the bracket and be moved to nested positions so that the cot when knocked down will occupy comparatively small space. The upper end of each post has an aperture 22 to receive a hook 23 and the said post is 80 further provided with an aperture 24 for receiving a hook 25, the shank of the said hook 25 being bent to form a loop 26 with an extension 27 extending at a tangent to the shank of the hook 25, the said extension 85 27 constituting a brace for a purpose to be presently explained.

The hooks of the posts at the head of the cot are connected by a flexible member 28 to which the fabric constituting the bed bottom is connected by means of the hooks 30, the said hooks being secured on the fabric by stitching or the like (not shown) and the said hooks engage the flexible member or coupling 28, as stated. 90

A jointed brace 31 is pivotally connected to the upper end of each of the posts 20 and the lower end of the said jointed brace is pivotally connected to the lower end of a leg 10 at the head of the cot. The hooks 23 100 are intended as attachments for the flexible members 32 to which the sides of the fabric 29 are connected, and these flexible members are connected to the posts at the foot of the cot by means of the metallic eyes 33, which 105 eyes are engaged by clips 34 passing

through links 35 extending from the posts 20 at the foot of the cot. The clip 34 has its end engaged by a loop 36 whereby it is retained in position to exert pull or tension on the flexible member which it controls. A hook 37 engages each of the posts 20 at the foot and the said hook has an extension 38 forming a guide as will presently appear. The hooks 37 at the foot are connected by a cable or flexible member 39 to be engaged by hooks 40 attached to the fabric 29, so that through the use of the hooks 30 and 40, the said fabric is connected to the framework of the cot at the head and foot.

15 A jointed brace 41 is pivotally connected to the post and leg on each side of the cot at the foot, and the feet at the head and foot of the cot are held in spaced relation transversely by the jointed braces 42, which jointed braces are pivotally connected to the said feet. A foot extension frame comprising the arms 43 and 44 and the cross rod 45 which is connected to the arms by the pivots 46 and 47, constitutes a support for an extension 49 of the fabric forming the bed bottom, and the said extension 49 is connected to the bar 45 by hooks 50. Arms 43 and 44 are preferably tubular and they extend between the shank of the hook 37 and the extension 38 of said hook and the ends of said arms are thrust longitudinally of the cot until they are engaged by hooks 51, which hooks are secured to the flexible member 32 in any well known manner. A foldable head rest is applied to the structure and it comprises two arms 52 and a bar 53 pivotally connected to the arms, brackets 54 to which the arms are pivotally connected and supporting members 55, which supporting members extend approximately vertically in engagement with the extension 27 of the hook 25 and said supports, at the lower ends, are cut away to form grooves 56 which provide clearances for the braces 31 so that the supporting members 55 sliding down the braces 31 engage the said braces and are held by the said braces and by the extension of the hook 25. If desired, the supporting members 55 may have stops 57 to engage the hooks for the purpose of eliminating their downward movement but such stops are not absolutely necessary for the reason that the braces 31 are inclined slightly and in their descent, the supporting members 55 are wedged between the braces. The head rest or the frame just described may be provided with canvas or other substitute.

The sections 17 and 18 of the strut-piece are preferably made of stamped sheet metal of such gage as to insure rigidity and durability and their inner ends are mounted on a pivot 58 and the said strut-pieces have cut away portions 59 and 60 which are intended to constitute clearances for the links or elements constituting the braces of the frame,

when the cot is folded. At each end of the pivot 58, there is a hinge 61 and the swinging portion 62 of the hinge has a pivot 63 on which an arm 64 may oscillate, it being shown in the drawing that the hinge will 70 permit the said arm to swing transversely of the cot whereas the pivot 63 will permit the arm to oscillate longitudinally, so that by the joints indicated, each arm 64 has nearly a universal movement with respect to 75 the strut-piece.

A spring 65 is connected to a hinge on each side and the opposite end of the said spring is connected to a lever 66, the said lever being pivoted on the end of an arm 80 64, it being understood that these parts are duplicated on the two sides of the cot. The upper end of the lever is recessed to form a seat 67, which engages the flexible member extending longitudinally of the cot and 85 to which the cot and bottom is attached. When the cot is occupied, the springs 65 yield to the weight of the occupant and the levers 66 oscillate so that a spring action is afforded, making the cot very comfortable. 90

In order to brace the structure, brackets 68 extend downwardly from the pivot, the lower ends of the said brackets converging and having a pin 69 extending through them, which pin constitutes a fulcrum for 95 a plate 70, the said plate having slots 71 and 72 therein to receive the ends of braces which are duplicated at each end of the cot. That is to say, the braces extend from the front and rear legs and are connected to 100 the plate 70 and, therefore, a description of one of the braces will suffice as a disclosure of the other.

It will be observed, therefore, that the braces comprise links 73 and 74 pivoted respectively to the legs on the right and left hand sides of the cot and that the said links have the ends remote from the legs pivotally connected to a plate 75 and another link 76 is pivotally connected to the said plate, and the said link 76 has an angular end or hook 77 which enters the slot of the plate. 105

As a further means for bracing the structure, jointed links are pivotally connected to the plate 70 and on pivots extending 115 through the strut-pieces. These parts are duplicated at each end of the frame and a description of those at one end will suffice for an understanding of the other. The last mentioned brace comprises a link 77 pivotally mounted to the plate 70, a short plate 78 to which the said link 77 is pivoted and a link 79 pivotally connected to the said plate 78 and to a pin 80 extending transversely of a section of the strut piece. 120

By reason of the numerous joints, the braces may be folded so that the parts of the cot will occupy a relatively small space and as provision has been made for pivoting the sections of the strut-piece and for pivot- 130

ing the legs so that they may be folded or nested, the whole structure may be compactly bundled for transportation or storage and when the cot is to be set up, the parts 5 thereof can be readily assembled to produce a rigid and effective frame.

We claim—

1. In a cot, front and rear supporting structures, a bed bottom applied to the rear 10 and front structures and supported thereby, levers connected to the sides of the said bed bottom, means to which each lever is pivotally connected, means for pivotally connecting the last mentioned means to the 15 supporting structure, and means for exerting tension on the said levers.
2. In a cot, front and rear supporting structures, a bed bottom supported from the rear and front structures, levers connected 20 to the sides of the said bed bottom, means to which each lever is pivotally connected, means for pivotally connecting the last mentioned means to the supporting structure, means for exerting tension on said levers, 25 and a head rest connected to the said frame.
3. In a cot, front and rear supporting

structures, a bed bottom supported from the rear and front structures, levers connected to the sides of the said bed bottom, a member for supporting each of the said levers, 30 means for connecting the said last mentioned means to the supporting structure, means for exerting tension on said levers, and posts supported by the structure and having extensions constituting a head rest. 35

4. In a cot, legs, brackets to which the upper ends of the legs are connected, a strut to which the brackets are connected, standards extending upwardly from the said brackets, a bed bottom, means for connecting the bed bottom to the standards, a plate intermediate the length of the said cot, braces extending from the lower ends of the legs to the said plate, braces extending from the said plate to the strut, levers, 40 means for mounting the levers to swing transversely of the cot, means for connecting the bed bottom to the said levers, and means for exerting a pull on the said levers for stretching the bed bottom. 45
